UNITED STATES PATENT OFFICE

111,521

DESIGN FOR A VERTICAL BUMPER

Louis S. Poncher, Chicago, Ill., assignor to Erie Manufacturing Company, Inc., Chicago, Ill., a corporation of Illinois

Application February 25, 1938, Serial No. 75,396

Term of patent 3½ years

To all whom it may concern:

Be it known that I, Louis S. Poncher, a citizen of the United States, residing at Chicago, in the county of Cook and State of Illinois, have invented a new, original, and ornamental Design for a Vertical Bumper, of which the following is a specification, reference being had to the accompanying drawing, forming a part thereof.

In the drawing:

Fig. 1 is a perspective view of a vertical bumper showing my new design.

Fig. 2 is a transverse sectional view taken on line 2—2 of Fig. 1.

I claim:

The ornamental design for a vertical bumper, as shown.

LOUIS S. PONCHER.
